FINGER RING STONE MOUNTING

William Lawrence Lewis, Indianapolis, Ind., assignor to Herff Jones Co., Indianapolis, Ind., a corporation of Indiana

Application February 6, 1952, Serial No. 270,183

1 Claim. (Cl. 63—15)

This invention relates to a means for mounting a stone on a finger ring, and particularly to means for interengaging a stone between a superimposed crest and a base portion whereby the stone is not subjected to undue stress tending to set up fractures and leading to breakage completely of the stone.

The invention contemplates the drawing down into fixed position of the stone against a resilient member so that when the securing means may be drawn up snugly, the stone will in turn be drawn down to a final position against that resilient means and be continued to be backed up thereby.

The primary advantage of the invention resides in the fact that breakage of the stone is reduced to a very low minimum, and moreover a tightness of the mounting of the stone is preserved over practically the life of the ring. Also, by use of the invention in the factory stones are readily mounted with a degree of speed, due to the fact that the stone is not mounted against a solid, non-resilient base as has heretofore been the case.

The invention may be applied to various stone mountings including the recessed mounting, or these mountings wherein there is a bezel entirely around the periphery of the stone, the bezel being rolled or peened over after the stone has been completely fixed in position.

Not only is the breakage of the stones reduced by use of the invention, but the workman is able to mount the stone with perhaps less skill and with more certainty of securing a rigid, tight mounting.

These and many other objects and advantages of the invention will become apparent to those versed in the art from the following description, which is made in reference to the accompanying drawing, in which

Fig. 1 is a view on an enlarged scale of a ring mounting in top plan;

Fig. 2 is a similar top plan view but with the stone and crest removed;

Fig. 3 is a view in section on the line 3—3 in Fig. 1; and

Fig. 4 is a detail in section transversely of the mounting.

While the invention may be applied to a great range of styles of mountings, it is herein shown as applied to a recess mounting. The shank 10 is prepared in the usual manner with a central flat area 11. A base 12 is formed to have a central opening 13 therethrough herein shown as being rectangular. This base 12 is affixed to the

shank in the usual and well known manner. Around the base opening 13, there is provided a ledge 14 entirely therearound as the margin of the opening 13. There is placed within the ledge 14 a spring member 16 in a generally H-shape to rest on the flat area 11. This member 16 has a transverse width slightly less than the transverse width of the opening 13, and is provided with the pairs of legs 17, 18, and 19, 20 on the opposite ends thereof. The overall length of the member 16 is less than that of the opening 13, and, moreover, this member 16 is arched in that it is concave from the underside and convex from the upper side as indicated in Figs. 3 and 4. The member 16 is made out of any suitable material which will be spring-like in nature, such as bronze or a beryllium copper composition.

Then a stone 15 is placed over the spring member 16 and a metal crest 21 having two down-turned posts 22 and 23 is brought over the stone 15, and these posts 22 and 23 are inserted downwardly through the stone 15, the stone 15 being provided with apertures 30 and 31 therefor, so that the posts 22 and 23 will pass between the arms 17, 18 and 19, 20 respectively, as indicated in Fig. 3. These posts may be solid or tubular as herein shown.

These posts 22, 23 have sufficient length to extend through and below the under side 32 of the shank 10, so that the extending ends of these posts 22, 23 may be flared, spun, peened, or riveted over against the under side 32 so as to draw down the crest 21 against the stone 15 and in turn to press it against the spring 16 to compress the spring 16 somewhat but still have the spring 16 yieldingly space the under side of the stone 15 above the ledge 14. The thickness vertically of the spring 16 is made to be such that when it is drawn down to that compression just indicated, it will preserve sufficient curvature to space the stone above the ledge.

The stone is preferably beveled on each end as at 33 and 34 so that the upturned base ends 35 and 36 may be worked over these ends 33 and 34 of the stone 15 to complete the mounting to prevent play endwise of the base. The stone 15 fits between the side walls 37 and 38 of the base.

Thus the stone 15 and its overlying crest 21 are very securely mounted on the shank 10 in a secure manner, and yet in a manner whereby the central area of the stone 15 is resiliently supported to be yieldingly held against possible fracture during the mounting operations as well as against breakage from accidental knocks when the ring is in use. In actual practice, the clear-

ance between the underside of the stone 15 and the ledge 14 is a minimum of five tenths of a millimeter. Also, the crest 21 is yieldingly held securely against the top side of the stone 15, whereby the crest cannot work loose in reference to the stone.

While the invention has herein been described and illustrated in the one particular form, as indicated, structural variations may be employed without departing from the spirit of the invention, and I therefore do not desire to be limited to that precise form beyond the limitations which may be imposed by the following claim.

I claim:

A finger ring stone mounting comprising a shank having a mounting floor area; spaced apart side walls outturned from said area; end walls outturned from said area at the ends of said side walls; a ledge around and within said walls at said floor defining the margin of a recess therewithin over said floor; an outwardly convex H spring positioned freely in said recess and confined therein by said ledge, said spring having a pair of spaced apart legs extending from a central zone of the spring along respective side walls in one direction and bearing by end portions on said floor, and a second pair of

20

25

spaced apart legs extending from said zone along those respective walls in the opposite direction and bearing by end portions on said floor; a stone resting on said central zone of said spring between and slidingly guided by said side walls in travel toward and away from said ledge; a crest on the outer side of the stone; a pair of spaced apart posts extending in fixed manner from said floor, one post on each side of said central zone and passing between the respective pairs of legs and through said stone to be fixed to said crest; the lengths of the posts between said floor and said crest being those which hold a stone compressively against said spring, placing the spring under compression, and having the spring space the stone outwardly from said ledge; and said end walls being abutted by ends of said stone.

WILLIAM LAWRENCE LEWIS.
